United States Patent Office

Des. 194,735
Patented Feb. 26, 1963

194,735

WATER SOFTENER

David Chapman, Chicago, Ill., assignor, by mesne assignments, to The Zeo-Ran Company, St. Paul, Minn., a corporation of Minnesota

Filed July 30, 1962, Ser. No. 71,074

Term of patent 14 years

(Cl. D91—1)

FIG. 1

FIG. 2

FIG. 3

FIG. 4

FIG. 1 is a front perspective view of a water softener showing my new design;

FIG. 2 is a rear perspective view thereof;

FIG. 3 is a front elevational view of the same; and

FIG. 4 is a fragmentary side elevational view thereof.

I claim:

The ornamental design for a water softener, substantially as shown.
